(57) **CLAIM**

The ornamental design for a star shaped container, as shown and described.

DESCRIPTION

FIG. 1 is a perspective view of a star shaped container of our new design.

FIG. 2 is a top plan view of the star shaped container of FIG. 1.

FIG. 3 is a bottom plan view of the star shaped container of FIG. 1.

FIG. 4 is a front elevational view of the star shaped container of FIG. 1.

FIG. 5 is a rear elevational view of the star shaped container of FIG. 1.

FIG. 6 is a side elevational view of the star shaped container of FIG. 1.

FIG. 7 is an opposite side elevational view of the star shaped container of FIG. 1.

FIG. 8 is a perspective view of a further embodiment of a star shaped container of our new design.

FIG. 9 is a top plan view of the star shaped container of FIG. 8.

FIG. 10 is a bottom plan view of the star shaped container of FIG. 8.

FIG. 11 is a front elevational view of the star shaped container of FIG. 8.

FIG. 12 is a rear elevational view of the star shaped container of FIG. 8.

FIG. 13 is a side elevational view of the star shaped container of FIG. 8; and,

FIG. 14 is an opposite side elevational view of the star shaped container of FIG. 8.
